ALBERT AICHELE, OF BADEN, SWITZERLAND, ASSIGNOR TO AKTIENGESELLSCHAFT BROWN BOVERI & CIE., OF BADEN, SWITZERLAND.

LIQUID RESISTANCE.

1,161,576.

Specification of Letters Patent. Patented Nov. 23, 1915.

Application filed December 26, 1913. Serial No. 808,877.

To all whom it may concern:

Be it known that I, ALBERT AICHELE, a citizen of the Swiss Republic, and residing at Wiesenstrasse 10, Baden, Switzerland, have invented certain new and useful Improvements in and Relating to Liquid Resistances, of which the following is a specification.

This invention relates to liquid resistances and has for its object to provide an improved resistance of this kind.

The invention consists in a liquid resistance in which the same resistance liquid is permanently subjected to a cycle comprising evaporation and condensation.

In the accompanying diagrammatic drawings: Figure 1 illustrates one manner of carrying the invention into effect. Fig. 2 illustrates a modification.

20 In the form illustrated in Fig. 1 the resistance liquid *d* is contained in a tank *b* above and in which is suspended a box *a* the lid of which carries a tube *l* open at each end. This tube is intended to allow raising 25 and lowering the under box *b*. If the top box *a* were entirely closed, then on raising the lower box *b* air or vapor would be compressed in *a* and the liquid would retain approximately its former level and would flow 30 over the edge of *b*; therefore in the rising of *b* the displaced air above the liquid must escape and when *b* is lowered air must be drawn in from the outside, otherwise it would be impracticable to regulate the resistance. The upper box *a* also carries the electrodes *c*. In this box a coil *e* is provided 35 with an inlet at *f* and an outlet at *g*. The space *h* between the upper box *a* and the lower tank *b* contains a layer of oil *i*. The 40 parts *a* and *b* are relatively movable, the drawing showing the top one fixed. In operation as the current passes through the resistance liquid it heats and evaporates the same, the vapor given off being condensed by 45 the coils *e* through which a cooling liquid flows. Vapor is prevented from escaping from the surface of the liquid between the parts *a* and *b* because of the layer of oil. The resistance is varied by moving the lower 50 tank upward and the outlet *l* permits this to be effected without difficulty as to change of

pressure. A resistance of this kind can be traversed by electric current for some considerable time or permanently and is very efficient. In this connection it may be 55 stated that if a resistance liquid is cooled in the ordinary way by circulation of water through cooling coils arranged therein, the temperature of the resistance liquid must not be greater than 60° to 70° C. or efficient 60 cooling cannot be secured. By arrangements according to the present invention in which cooling coils are disposed not in the liquid but in the vapor thereof the temperature of the resistance liquid can be approxi- 65 mately 100° C. We find this has certain advantages; among others the size and cost of a water resistance for a given electrical capacity may be reduced. Also as the same resistance liquid is used continuously in- 70 crustation is almost entirely avoided.

It will be understood that the form of the invention given above is described by way of example only. A modification is illustrated in Fig. 2. In this, instead of placing the 75 cooling coils *e* inside the top vessel *a* they are placed outside, namely in a vessel *a'* and the vapor from the resistance liquid is supplied to them by the pipe *o*; this vapor there- 80 fore being helped to condense by the cooling action of the air on the vessel. The condensed liquid can conveniently collect in the water pocket *r* and be returned to the vessel *b* for instance through the channel *h*. The vessel *a'* is provided with a valve *n* opening 85 in both directions but which is normally closed when the pressures on each side are equal. This valve may be interchanged with the pipe *l* if desired.

Having now described my invention what 90 I claim as new and desire to secure by Letters Patent is:—

1. An electric resistance comprising a tank containing a liquid, a fixed tank disposed above and dipping into the liquid in 95 said first tank, electrodes depending from the cover of said fixed tank and means for condensing evaporated liquid.

2. An electric resistance comprising a tank containing a liquid, an inverted tank fixed 100 above said first tank and sealed by the liquid therein, electrodes depending from the top

of said second tank into the liquid in said first tank, a cooling coil arranged in the second tank and above the liquid in the first tank together with means for permitting entry and egress of vapor from said second tank.

In testimony whereof I have affixed my signature in presence of two witnesses.

ALBERT AICHELE.
